UNITED STATES PATENT OFFICE.

JOHN HENRY NEILL, OF SINCLAIRVILLE, NEW YORK.

HARNESS-BUCKLE.

SPECIFICATION forming part of Letters Patent No. 373,245, dated November 15, 1887.

Application filed March 29, 1887. Serial No. 232,869. (No model.)

To all whom it may concern:

Be it known that I, JOHN HENRY NEILL, of Sinclairville, in the county of Chautauqua and State of New York, have invented a new and 5 Improved Harness-Buckle, of which the following is a full, clear, and exact description.

My invention relates to an improved buckle, designed more particularly for use on the crupper and hip-straps of harness, the object 10 being to provide a practical buckle which will not catch the hair of a horse's tail, and under which the line cannot be caught, as with the ordinary form of buckles, and which will prevent the line from catching under the end of 15 the hip-strap.

Reference is to be had to the accompanying drawings, forming a part of this specification, in which similar letters of reference indicate corresponding parts in both the figures.

20 Figure 1 is a plan view showing my new form of buckle applied to a hip-strap, and showing the angle-straps which lead to the breeching of the harness; and Fig. 2 is a sectional elevation of the same.

25 A represents the body of the buckle, formed in the center with the stud *a*, which enters the holes in the strap *B* and serves as a tongue to retain the strap. At its upper end the body *A* is formed with the loop *C*, which stands a 30 sufficient distance above the body *A* to permit the ready insertion of the strap *B*, and at

its lower end the body *A* is formed with the ring *D*, which also constitutes a loop, *D'*, for the strap *B*. The loops *C* *D'*, one above and the other below the stud *a*, hold the strap in 35 contact with the body *A*, so that there is no danger of its detachment from the stud *a*. The ring *D* is on a higher level than the body *A*, so that it stands in front of the strap *B*, and to it are connected the two straps *B' B'*, which 40 connect with the breeching. In this manner the straps *B'* and ring *D* entirely prevent the lines from catching under the hip-strap, and the stud *a*, not being exposed above the outer surface of the strap *B*, will not catch the horse's 45 tail. Each side of the stud *a*, I form a hole, *f*, through which rivets may be passed for securing the buckle to the strap.

Having thus described my invention, what I claim as new, and desire to secure by Letters 50 Patent, is—

The improved buckle herein described, comprising the body *A*, having stud *a*, the loop *C* at one end and the loop *D'* at the other, and the ring *D*, formed as a part of the loop *D'* 55 and on a higher level than the body *A*, substantially as described.

JOHN HENRY NEILL.
